(57) **CLAIM**

The ornamental design for a “mirror assembly,” as shown and described.

DESCRIPTION

FIG. 1 is a front left perspective view of a mirror assembly showing our new design, wherein the mirror is located on the front of the mirror assembly and is mounted in a mirror housing;

FIG. 2 is a front view thereof;

FIG. 3 is a rear view thereof;

FIG. 4 is a plan view thereof;

FIG. 5 is a bottom view thereof;

FIG. 6 is a right side elevational view thereof, with the left side being a mirror image of the right side;

FIG. 7 is a front left perspective view of a mirror assembly of FIG. 1 oriented in an extended position;

FIG. 8 is a front view thereof;

FIG. 9 is a rear view thereof;

FIG. 10 is a plan view thereof;

FIG. 11 is a bottom view thereof;

FIG. 12 is a right side elevational view thereof;

FIG. 13 is a left side elevational view thereof;

FIG. 14 is a front left perspective view of a mirror assembly of FIG. 1 oriented in an extended position with the mirror tilted upward thereof;

FIG. 15 is a front view thereof;

FIG. 16 is a rear view thereof;

FIG. 17 is a plan view thereof;

FIG. 18 is a bottom view thereof;

FIG. 19 is a left side elevational view thereof;

FIG. 20 is a right side elevational view thereof;

FIG. 21 is a front left perspective view of a mirror assembly of FIG. 1 oriented in an extended position with the mirror tilted downward;

FIG. 22 is a front view thereof;

FIG. 23 is a rear view thereof;

FIG. 24 is a plan view thereof;

FIG. 25 is a bottom view thereof;

FIG. 26 is a right side elevational view thereof;

FIG. 27 is a left side elevational view thereof;

FIG. 28 is a front view of the mirror and mirror housing of the mirror assembly of FIG. 1, shown separately for clarity;

FIG. 29 is a rear view thereof;

FIG. 30 is a right side elevational view thereof;

FIG. 31 is a left side elevational view thereof;

FIG. 32 is a plan view thereof;

FIG. 33 is a bottom view thereof;

FIG. 34 is a rear view of the mirror, the mirror housing and a connecting bracket of the mirror assembly of FIG. 1, shown separately for clarity;

FIG. 35 is a right side elevational view thereof;

FIG. 36 is a left side elevational view thereof;

FIG. 37 is a plan view thereof; and,

FIG. 38 is a bottom view thereof.
